TICKING TOY WATCH

Lawrence Wise, Cedarhurst, N. Y., assignor to
 Ever Tick Corporation, Floral Park, N. Y., a
 corporation of New York

Application June 1, 1950, Serial No. 165,416

16 Claims. (Cl. 58—106)

1

My present invention is an improvement of the invention described in my application Serial No. 135,730, filed December 29, 1949, and relates primarily to the specific commercial embodiment of the toy watch made in accordance with the disclosure thereof.

The invention is directed to a ticking element for a toy watch and to other operative elements of the watch so arranged as to simplify manufacture and assembly.

The objects of my invention will become apparent in the following description and drawings in which:

Figure 1 is a plan view of my novel toy watch with the back removed.

Figure 2 is a view of the face of my toy watch.

Figure 3 is a cross-sectional view taken on line 3—3 of Figure 1.

Figure 4 is a view in perspective of the interior of the watch case.

Figure 5 is a cross-sectional view corresponding to that of Figure 3 showing the method of assembly.

Figure 6 is a diagrammatic view showing the method of operation of the ticking element.

Referring to Figures 1 to 4, I have here shown the front half 10 of a watch case to which any suitable back cover may be secured.

The front half 10 of the watch case has a front surface 11 and a wall 12 which may be annular in the case of a circular front wall 11 but which in any event follows the outer perimeter of the front wall 11 and is perpendicular thereto.

The back cover 13 may be secured to the free end of the wall 12 or tightly fitted over it in any suitable manner.

Gear wheel 16 has hands 19 struck up therefrom. Hands 19 (as seen in Figure 5) may be passed through opening 18 in the front wall 11 and then bent over the printed face card 20 which covers the openings in wall 11.

The teeth of gear wheel 16 are bent up as shown to make a type of bevel gear to cooperate with the hand winder knob described below.

The front wall member 11 is a single plate having all of the securement elements thereon.

The hand wind arbor 26 is mounted in recess 25 in wall 12 and is supported in lug 25a of wall 11. The pinion 27 and knurled knob 28 are made integral with arbor 26.

Thus, assembly is facilitated. The gear wheel 16 is positioned by pushing the hands 19 struck up therefrom in opening 18 in wall 11. The hands 19 pass through face card 20 and, when bent over, position gear wheel 16 and face card

2

28. The winding element is merely snapped into lug 25a and is positioned by matching recesses in walls 12 and 13.

The wall 12 may have a bezel 29 to receive a crystal 29a. The face card 20 may be replaced by appropriate lithographing or other printing on the front wall 11 itself.

The ticking element of my novel toy wrist watch comprises the leaf spring 30 which, as pointed out in application Serial No. 135,730, above referred to, is preferably made of feeler gauge stock approximately .0015 inch thick, $\frac{1}{8}$ inch wide and .875 inch long of oil hardened steel.

One end of leaf spring 30 is welded between the 15 two upstanding lugs 32 struck up from wall 11.

The spring 30 is so arranged that its width (not its thickness) is perpendicular to the front wall 11, but it is supported free of the front and back walls 11 and 13. The free end of the spring 30 has clamped thereto or secured thereto in any suitable manner a weight 35 so dimensioned that as the spring vibrates the weight 35 will always be clear of the front and back walls of the casing.

A lateral arm 40 is secured on each side to the 25 side of spring 30 by welding on the bent over panel 41. Arms 40 are engageable with respective lugs 14 struck up from wall 11, as the spring oscillates, to produce a ticking sound.

Thus, the spring 30 may readily be assembled 30 in the watch by placing the same between lugs 32 and applying welding electrodes to the outer surfaces of lugs 32.

When the spring 30 is mounted in the watch case as shown, any movement such as that occasioned by the movement of the watch case either when it is picked up from a store counter and placed to the ear or when it is moved on the wrist to the ear will cause the spring to vibrate as a pendulum about its anchor point 32. This 40 motion is illustrated in Figure 6.

I have found with a spring of the type and dimensions above-described a single motion from the counter to the ear, from the wrist to the ear, or from one portion of the counter to the other will produce a ticking lasting for forty seconds or more.

The ticking will occur and continue irrespective of the orientation of the watch—face up, face down or vertical and at any angle.

By this means, therefore, I provide an inexpensive ticker for a toy watch which may readily be incorporated in existing toy watch designs and will provide the child with the satisfaction of 55 owning a ticking watch. A watch with my novel

ticking device may, nevertheless, be sold as an inexpensive toy watch in the ten cent stores.

The leaf spring 30, the arm 40 and the lug 14 with which it cooperates to produce the ticking noise are so mounted that for any normal movement of the watch the oscillations will occur without any inhibiting force. The operability of my device is probably due to the transformation of kinetic to potential energy and back again as the weight oscillates. Thus, the energy of the oscillating weight, which is kinetic when the weight is going in one direction, and prior to the engagement of an arm 40 with a lug 14, changes to potential energy in causing flexure of the spring once such engagement has occurred. Thus, the tick effected by the engagement does not utilize the entire kinetic energy of the weight, a large portion of the kinetic energy being then transformed to potential energy in bending the spring. Accordingly, as the spring unbends to swing the weight back in the reverse direction, the potential energy of the bent spring is transformed back into the kinetic energy of the moving weight only to be once more transformed to potential energy upon occurrence of engagement of the other arm 40 with its respective lug 14. Thus, the cycle of transformation of energy from kinetic to potential is sustained for an appreciable period while the ticking of the mechanism absorbs only a portion of such energy during each cycle. That this explanation is probably true may be inferred from the fact that if a mere spring was set oscillating with a weight at the end intended to strike lugs disposed at the ends of the swing, to produce a ticking sound, it would not work more than one or two cycles because all of the kinetic energy of the weight, and such potential energy as may be stored in the spring, would be absorbed in shock and deformation, however minute, of the abutting elements. The preceding contention has been determined by experimentation and strongly indicates that my theory of operability is correct.

The utilization of two arms 40 against lugs 14 makes the tick rapid and steady.

By the means herein described, a simplified assembly is permitted. The hands and the gear wheel are made of one piece; the winding knob and its gear and arbor are one piece; the ticking spring is accurately positioned by the main support panel or wall.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall.

2. A toy watch having a front wall, an opening in the front wall; a gear wheel parallel to the front wall, watch hands struck up from the gear wheel and passing through the opening in the front wall; said watch hands being bent parallel to the front wall.

3. A toy watch having a front wall, an opening in the front wall; a gear wheel parallel to the front wall, watch hands secured to the gear wheel and passing through the opening in the front

wall and having bearing support in said opening for rotatively supporting said gear wheel; said watch hands being bent parallel to the front wall, and a pinion meshing with said gear wheel; a winding knob; an arbor connecting said winding knob and pinion; said winding knob and pinion and arbor being integral.

4. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall, the teeth of the pinion wheel being bent at an angle to the gear wheel, a gear meshing with said gear wheel; a winding knob connected to said pinion.

5. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall, the teeth of the pinion wheel being bent at an angle to the gear wheel, and a pinion meshing with said pinion wheel; a winding knob; an arbor connecting said winding knob and gear; said winding knob and gear and arbor being integral.

6. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall, and a pinion meshing with said gear wheel; a winding knob; an arbor connecting said winding knob and pinion; a recessed lug struck from said front wall; the arbor being positioned in the recess of the lug.

7. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall, and a pinion meshing with said gear wheel; a winding knob; an arbor connecting said winding knob and pinion; a recessed lug struck from said front wall; the arbor being positioned in the recess of the lug; an additional pair of lugs struck from said front wall; a ticking member; said ticking member being secured between said pair of lugs.

8. A toy watch having a front wall, an opening in the front wall; a gear wheel parallel to the front wall, watch hands secured to the gear wheel and passing through the opening in the front wall and having bearing support in said opening for rotatively supporting said gear wheel; said watch hands being bent parallel to the front wall, and a pinion meshing with said gear wheel; a winding knob; an arbor connecting said winding knob and gear; a recessed lug struck from said front wall; the arbor being positioned in the recess of the lug; an additional pair of lugs struck from said front wall; a ticking member; said ticking member being secured between said pair of lugs; a further lug struck from said front wall; said ticking member cooperating with said further lug to produce a ticking noise.

9. A toy ticking device for watches or the like having a wall and a ticking member including a flat spring extending with a longitudinal edge

thereof parallel to said wall with the flat surface thereof normal to the wall, a weight at one end of said spring; a securing means comprising a lug on said front wall; the other end of said spring being secured to said lug, an arm on said spring; an additional lug struck from said wall; said arm cooperating with said additional lug to produce a ticking noise.

10. A ticker for a toy device comprising a base, said ticker having a spring and means for anchoring one end of said spring to said base, the opposite end of the spring being free to oscillate a weight at said opposite end of the spring, and a percussion element carried by said spring intermediate the ends.

11. A ticker for a toy device, as set forth in claim 10, wherein said percussion element is disposed on said spring substantially closer to the anchored end thereof.

12. A ticker for a toy device comprising a base, said ticker comprising a spring having one end anchored to said base and a weight at the other end, said other end being free to oscillate, including a pair of percussion elements, at least one of which is carried by said spring intermediate the ends, whereby as said spring oscillates, said percussion elements engage each other to produce a ticking sound and thereby consuming a portion of the kinetic energy of said moving weight; said weight continuing to move and flexing the portion of said spring outwardly of the percussion element carried thereby so as to transform the remaining kinetic energy of said moving weight into the potential energy of flexure of said spring, wherein said potential energy is transformed back into kinetic energy in the return oscillation of said weight, all for the purpose of sustaining oscillation of said spring for as long a period as possible by utilizing only a portion of the energy available for producing a ticking sound at each oscillation.

13. A ticker for a toy device, as set forth in claim 10, wherein said spring comprises a leaf approximately .875 of an inch long, $\frac{1}{8}$ inch wide, and .0015 inch thick, of oil hardened steel.

14. A ticking noise maker comprising an enclosure, a leaf spring; means for anchoring one end of said leaf spring in said enclosure; the opposite end of the leaf spring being free to oscillate; a weight at the said opposite end of the leaf spring, and means intermediate the ends of the leaf spring for translating oscillations of the leaf spring into sound; said means comprising an arm substantially normal to the leaf spring and secured thereto closer to the anchored end than to the free end, and a stationary member positioned to be struck by said arm at each oscillation of the leaf spring.

15. A ticker for a toy case, said ticker comprising a leaf spring; means for anchoring one end of said leaf spring within the case; the opposite end of the leaf spring being free to oscillate; a weight at said opposite end of the leaf spring; and means intermediate the ends of the leaf spring for translating oscillations of the leaf spring into sound; said means comprising an arm substantially normal to the leaf spring and secured thereto closer to the anchored end than to the free end and a stationary member positioned to be struck by said arm at each oscillation of the leaf spring; the leaf spring during the portion of each oscillation when the arm engages the stationary member oscillating about approximately the point of securement of the arm to the leaf spring.
16. A ticker for a toy watch case, said ticker comprising a leaf spring; means for anchoring one end of said leaf spring within the watch case, the opposite end of the leaf spring being free to oscillate; a weight at said opposite end of the leaf spring; and means intermediate the ends of the leaf spring for translating oscillations of the leaf spring into sound; said means comprising an arm substantially normal to the leaf spring and secured thereto closer to the anchored end than to the free end and a stationary member positioned to be struck by said arm at each oscillation of the leaf spring; the leaf spring during the portion of each oscillation when the arm engages the stationary member oscillating about approximately the point of securement of the arm to the leaf spring and during the remainder of each oscillation oscillating about approximately the point of securement of the leaf spring to the watch case; the watch case comprising two spaced substantially parallel walls and a peripheral wall connecting said parallel walls; the leaf spring being mounted normal to the parallel walls and spaced therefrom.
